(57) **CLAIM**

The ornamental design for a corner device for a floor covering, as shown and described.

DESCRIPTION

FIG. 1 is a perspective view of a first embodiment of a corner device for a floor covering showing my new design in a position of use on an environmental floor covering, which is shown pulled back by a user;

FIG. 2 is a bottom plan view thereof;

FIG. 3 is a top plan view thereof;

FIG. 4 is a front elevation view thereof;

FIG. 5 is a right elevation view thereof;

FIG. 6 is a bottom plan view thereof, shown in an alternate configuration; and,

FIG. 7 is a top plan view thereof, shown in the alternate configuration.

The broken lines in the drawings depict environment that forms no part of the claim.
